UNITED STATES PATENT OFFICE

CHARLES W. PRESCOTT, OF ROCHESTER, NEW YORK, ASSIGNOR TO GENERAL RAILWAY SIGNAL COMPANY, OF ROCHESTER, NEW YORK

INDICATING SYSTEM FOR LIGHT SIGNALS

Application filed February 23, 1926. Serial No. 90,062.

This invention relates to railway traffic controlling systems, and more particularly to a system for controlling interlocking mechanism in accordance with the indicating conditions of light signals and protected by cross-protection and tower indicating means.

In the provision of light signals for railway signaling purposes, difficulty has been experienced in obtaining a reliable indication 10 in the tower as to the indicating condition of a wayside light signal, and difficulty has been experienced in providing proper protection against the display of a favorable traffic indicating condition possibly by the 15 reason of false current due to a cross, ground, or the like, at a time when a conflicting route is set up; adequate means for indicating the condition of light signals by itself has, however, been disclosed in a general way in my 20 prior application Serial No. 725,389 filed July 11, 1924.

The present invention relates more particularly to a more complete system of light signaling for railways, and the object of the 25 present invention resides primarily in the provision of adequate indicating means at the tower for indicating the condition of a light signal, and to means for protecting the wayside signals against giving a false clear indication due to crosses, and the like, that is, the 30 giving of a proceed indication when such an indication is improper and dangerous. A further object of the present invention, resides in the provision of additional electrical 35 checks and shunting contacts, so as to assure against a false signal indication; and further resides in the provision of automatic means for preventing a danger wayside signal lamp from being extinguished until a proceed wayside signal lamp is illuminated, and for causing the danger lamp to be illuminated if the 40 proceed lamp is extinguished.

Other objects, purposes and characteristic 45 features of the invention will appear as the description of the several embodiments thereof progresses.

In describing the invention in detail reference will be made to the accompanying drawing in which:

Fig. 1 shows a semi-automatic light signal

system in which visual proceed and stop indications are given at the tower in response to the illumination of proceed signals and a stop signal respectively, by signal lamps of the "Fleming valve" type, this indication being given over a single wire and by a polarized 55 relay in response to the polarity of the rectified current derived from the particular signal lamp illuminated at the time, and in which the lever is prevented from being removed 60 to the normal position when in the indicating position unless the danger lamp filament is incandescent;

Fig. 2 shows a system similar to that illustrated in Fig. 1, in which the provision for giving a proceed signal indication in the tower has been omitted, and in which the failure of the circuit of a proceed lamp at a time when such proceed lamp should be illuminated 65 automatically illuminates the danger 70 lamp;

Fig. 3 shows a wholly automatic signal for automatic block signal territory, in which means are provided whereby the failure of the circuit of a proceed lamp illuminates the 75 danger lamp when such proceed lamp should be illuminated; and

Fig. 4 shows a semi-automatic interlocking system in which cross-protection is provided by having the proceed relay checked 80 against false energization thereof by crosses, this by having this relay in multiple with a repeatedly checked partial circuit including the cross-protection relay, so that the application of false current to the proceed relay 85 causes energy to be cut off of the system, by the cross-protection relay.

Referring to Fig. 1, in which a traffic controlling system has been illustrated embodying certain features of the present invention 90 shows a trackway comprising rails 1 divided by insulating joints 2 into blocks of which the block I and the adjacent ends of other blocks H and J only have been shown. The blocks I and J are provided with track relays 95 T and T¹ respectively at the entrance end thereof, and these blocks are provided with the usual trackway source of energy such as batteries 3 illustrated at the exit ends of the blocks H and I. At the entrance end of the 100

block I is located a semi-automatic stop-and-stay interlocking light signal S; whereas the entrance end of the block J is provided with the automatic light signal S¹ embodying certain features of the present invention. The signal S located at the entrance end of the block I and its control circuits are more specifically shown in the wiring diagram of Fig. 1; whereas the wiring arrangement for the signal S¹ is shown in Fig. 3. The signal S in Fig. 1 includes lamp signal casings having colored lenses to give distinctive light signal indications corresponding to clear, caution and danger by colors such as green, yellow and red, as illustrated by the lamps G, Y and R. These lamps are of the Fleming valve type, each of which includes a filament F and an anode, or plate, P.

The signal S, as heretofore mentioned, is a semi-automatic interlocked light signal, and therefore is automatically controlled but has superimposed thereon manual control by suitable lever mechanism which is interlocked with conflicting lever controlling other signals, switches, derails and the like, as is common practice in interlocking systems. In the particular arrangement shown the signal S is normally held at danger by contacts controlled by the lever L in the interlocking tower, even though traffic conditions in the blocks I and J are favorable as illustrated in Fig. 1. With the block I and J unoccupied the energizing circuit for the line relay LR, including front contacts 5 and 6 of the relays T and T¹ respectively, is closed so that the relay LR is energized.

Adjacent the signal S is located a main relay MR for controlling the same which relay in the particular arrangement illustrated comprises a polyphase or three-position electroresponsive device of the alternating current induction type. The winding 8 of this relay MR is connected directly across the alternating current mains 7 and 9 which derive their energy from the secondary winding of the transformer 4 so that one phase winding of the relay MR is always energized. The other winding 11 of the relay MR is normally shunted or short circuited by the contacts 12-13 of the lever L, so that it is very unlikely that energy will be supplied to the winding 11 of this relay accidentally. Suitable means (not shown) is preferably provided in connection with the winding 8 to effect the necessary phase displacement between the currents flowing in the winding 8 and 11 to effect proper operation of the relay. With the relay MR de-energized, as it is when the lever L is in the normal position, the transformer connected to the filament F of the lamp R is energized through the following circuit:—beginning at the line wire 7, leading from the transformer 4 wires 18 and 19, contact 20 of the main relay MR, wire 21, primary winding of the transformer 22, wires

23 and 24, to the other line wire 9 connected to said transformer 4. With the filament F incandescent, and with an alternating current potential due to the portion 25 of the secondary winding of the transformer 22 impressed across the plate and the filament of the lamp R, a pulsating current due to the rectifying action of the Fleming valve flows in the following circuit:—beginning at the filament of lamp R, portion 25 of the secondary winding of the transformer 22, wires 26, 27 and 28 winding of the indication relay IR, locked in the tower, wires 29 and 30, contacts 31 and 32 controlled by the lever L, wires 33 and 34, winding of the cross-protection relay CR, wire 35, contacts 36 and 37 of the cross-protection relay CR, wire 38 then through wires 9, 24, 23, and 39 to the plate P of the lamp R. It will be noted that the current flowing in the circuit just traced is pulsating in character and flows from right to left through the indication relay IR, and current of this polarity causes contacts 43 and 44 of this relay to assume the left hand position thereby energizing the danger lamp r.

It is thus noted that a reliable indication is given at the tower, which indication can only be present if the lamp R is energized. Because the indication current is uni-directional in character whereas the source of supply is alternating in character and the polarity of this uni-directional current is different from that of the indication current derivable from the lamps G and Y, as more clearly pointed out hereinafter.

Let us now assume that the lever L is moved to the reverse position, the extreme right hand position in Fig. 1. As the lever is moved toward the right the shunting contacts 12-13 and 31-32 are opened when the lever passes the half reverse position. As the lever reaches the full reverse position the left hand connection of the indication relay IR is connected directly to the line wire 9 of transformer 4; also, the winding 11 of the main relay MR, which is no longer shunted, is connected directly to the contacts 47 and 48 of the line relay LR. Under this condition the relay MR will assume the right hand and left hand position when the line relay LR is energized and de-energized, respectively; and further, the main relay MR is de-energized even though the lever L is in the reverse position if a track relay T is de-energized and the contacts 50 and 51 entirely disconnect the transformer 52 from the pole changing contacts of the line relay LR.

Let us assume that the blocks I and J are not occupied, and with the lever L removed to the reverse position, the main relay MR is operated toward the right, so that the transformer 53 for supplying the filament F of the lamp G is energized through a circuit readily traced in the drawings. With this lamp G incandescent the potential due

to the portion 53¹ of the transformer 53 impressed across the plate and filament of the lamp G causes a current to flow from plate to filament in the following circuit:—beginning at filament F, portion 53¹ of the transformer 53, wires 54, 55 and 24, wire 9, wire 56, contacts 57—58 controlled by the lever L, wires 59 and 29, winding of the indication relay IR, wires 28, 27, 60 and 61 to the plate 10 P of the lamp G. It will be noted that the indication current at this time flowed from left to right through the indicator relay IR, so that this relay now assumes the right hand dotted position and energizes the indication 15 lamp g—y. In other words, the lamp G is connected to the indication circuit reversely from that of the lamp R, so that the rectified pulsating current flows through the indication relay IR in the reverse direction. If 20 now, the block J becomes occupied, or the track relay T¹ assumes its de-energized position for some other reason, the line relay LR is de-energized and the polarity of the alternating current applied to the winding 25 11 of the main relay MR is reversed, so that this relay assumes its left hand position and thereby illuminates the lamp Y instead of the lamp G. It is considered unnecessary to trace the energizing circuit for the lamp Y 30 or the indication circuit including the lamp Y and the indication relay IR since these circuits are substantially the same as those for the lamp G.

Let us now assume that the operator in the 35 tower wishes to display a danger signal by the signal S for the purpose of stopping a train which might endanger another train if the first mentioned train passed the signal S and in order for the operator to allow said 40 another train to proceed he is required to put the lever L in its normal position, this in order to unlock another lever to permit said another train to proceed, all of which is accomplished by suitable mechanical or 45 electrical interlocking mechanism between levers, as well known to those skilled in the art of interlocking. If the towerman moves the lever L toward the normal position, the indication magnet IM being de-energized 50 the lever will be stopped when it reaches the half normal position in which position the contacts 58—65 are closed, and the projecting pin 66 of the indication magnet IM engages the shoulder 67 of the lever L. Since, however, 55 this movement of the lever L causes the main relay MR to assume its de-energized position the lamp R is presumably lighted, and if this lamp is not out of order an indication current will flow through the same 60 circuit as heretofore traced when the lever L was in the normal position, but in the present instance the indication magnet IM is connected in multiple across the indication relay IR through a circuit including the contacts 58—65 as clearly shown in the draw-

ings. The flow of this indication current energizes the indication magnet IM and permits the operator to complete the movement of his lever to the full normal position, in which position certain conflicting levers are unlocked, thus permitting the operator to allow certain trains moving on conflicting routes to proceed.

It will be pointed out at this time, that the indication magnet IM is preferably responsive to uni-directional current only, so that it is very unlikely for the lever L to be accidentally unlocked due to alternating current flowing on account of crosses, or the like. Also, the cross-protection relay CR which is connected in series with the indication magnet, is one of the type in which its contacts are normally held closed by flux emanating from the permanent magnet PM forming the bottom yoke of this cross-protection relay, the top yoke 70 of this relay preferably comprising soft iron, and if indication current uni-directional in character flows through the coil in such a direction that the magnetic flux emanating from the permanent magnet PM is not shunted away from the yoke 70 this cross-protection relay is not actuated by indication current derived from lamp R.

Since, under normal operating conditions only pulsating indication current of a polarity so as not to rob the yoke 70 of its permanent magnet flux is required to flow through this cross-protection relay CR this relay will not open in response thereto but if pulsating current of the reverse polarity or if alternating current should be applied to the cross-protection relay CR its contacts 36—37, 40—41, are opened, and the circuit for energizing the same will be broken at the contacts 36—37. Also, in the event the cross-protection relay is operated the contacts 40—41 are opened and cut energy off of the transformer 52, so that the relay MR cannot be energized, and a proceed indication cannot be given although the danger lamp R will not be robbed of its energizing current and will continue to indicate danger. In this connection, it is desired to be pointed out that the proceed signal lamps G and Y may be ordinary lamps if desired, and the proceed indication current may be supplied directly to the indication relay IR from a suitable source of current through contacts controlled directly by the main relay MR, these contacts completing a circuit to apply the proper potential to the indication three position relay IR to cause it to assume a position corresponding to the position the relay MR is assuming at the time.

In systems, such as just described, wherein a plurality of semi-automatic light signals are employed it may be desirable for the operator to be informed whenever a filament anywhere in the whole system burns out. To

illustrate applicant's arrangement whereby this may be accomplished the indication relay IR^a of another signal lever has been shown. The bell ringing relay 46 is connected in an energizing circuit including the various normal and reverse contacts 45, 45^a etc. of three position relays, or if polar neutral relays are used the neutral contacts thereof are connected in series. As indicated the bell 49 is sounded when the relay 46 is de-energized.

By this arrangement if there is an indication relay anywhere in the system which is not energized either positively or negatively that is, is de-energized because there is no indication current flowing, the bell 49 is sounded. By this arrangement an audible signal is sounded when there is a dark or non-indicating multiple aspect color light signal anywhere in the interlocking plant.

Summing up the features of the form of the invention shown in Fig. 1, the arrangement shown provides means whereby the main relay is protected against false energization by crosses or the like by having one of its field coils shunted for all positions of the lever except the reverse position; provides means for cutting energy off of all equipment except the danger lamp when alternating current, or uni-directional current of the wrong polarity traverse the indication magnet and cross protection relay connected in series therewith, so that it is very unlikely for a proceed lamp to be illuminated when the lever is normal, also it is very unlikely for the lever to be unlocked due to false current at a time when the lamp R is not illuminated. Further the embodiment in Fig. 1 discloses reliable visual and audible indication means for informing the operator as to the indicating conditions of the various multiple unit color light signals.

In Fig. 2 of the drawings has been shown a system which is in many respects the same as that shown in Fig. 1, and for this reason as the portion shown in the dotted rectangle in Fig. 1, as well as the trackway apparatus, have been omitted. Since many of the elements of the system shown in Fig. 2 are the same as those shown in Fig. 1 such elements have been assigned like reference characters. The main difference of the disclosure in Fig. 2 from that shown in Fig. 1 is that the indication circuit leading from the lamps G and Y to the indication relay IR has been omitted.

Another feature resides in the provision of a danger relay DR which is energized when the main relay MR is energized providing that the particular lamp G or Y lighted for the particular position of the main relay MR has its filament intact and is lighted and is providing indication current through the danger relay DR. This circuit arrangement automatically substitutes the danger indication for a proceed indication if the filament of the proceed lamp fails.

Let us assume that the main relay MR assumes its right hand position and the clear lamp G is illuminated for reasons given in connection with Fig. 1 of the drawings. With lamp G incandescent the portion 53¹ of the secondary winding of the transformer 53 supplies the necessary potential to cause rectified pulsating current to flow through the following circuit:—beginning at the filament F of the lamp G, the portions 53¹ of the transformer 53, wires 54, 55, 24, 9, 75 and 76, winding of the danger relay DR, wires 77 and 78, contact 79 to the main relay MR in either of its extreme positions, wires 80 and 81 back to the plate P of the lamp G. If now, for any reason, the lamp G should fail to be illuminated, probably because its filament is burned out or an essential wire for energizing the same has been broken, indication current no longer will flow to the danger relay DR and this relay will assume its de-energized position. With the danger relay DR de-energized the following energizing circuit for the danger lamp R is completed:—beginning at the wire 7 leading from transformer 4 wires 18 and 84 back contact 85 of the danger relay DR, wire 86 primary winding of the transformer 22, wires 87 and 88 and 24 back to the wire 9. With the danger lamp R incandescent the indication relay IR is energized to a position to illuminate the indicating lamp r, and if the lever L is moved to the half normal position the indication magnet IM is energized in a manner as already clearly described in connection with Fig. 1 of the drawings. In other words, the system shown in Fig. 2 is the same as that shown in Fig. 1 except that the indication current derivable from lamps G and Y is used for maintaining the danger lamp R cut off, that is, the indication current from the lamp G or Y as the case may be, maintains the danger relay DR energized and in so doing cuts energy off of the red lamp R. Also, the indication relay IR is only connected in the indication circuit leading from the danger lamp R, so that, this indication relay IR is only energized when the red lamp R is energized and gives a visual indication at the tower under danger traffic conditions of the signal S only, and further indication current permits unlocking of the lever only if the danger lamp R is illuminated for reasons given in connection with the description of Fig. 1.

In Fig. 3 of the drawings have been illustrated the control circuits for the lamps of the three condition signal S¹ shown in Fig. 1 for use in automatic signal territory. Under normal clear traffic conditions the track relay T¹ and the line relay LR¹ are energized and thus illuminate the green lamp G¹ through the following circuit:—beginning at the secondary winding of the transformer 100, wire 101, front contact 102 of the track relay

T^1 , wire 103, front contact 104 of the line relay LR^1 , wire 105 primary winding of the transformer 106 connected to the filament of the lamp G^1 , wires 110, 107, 111 and 108 back to the secondary winding of the transformer 100. With the green lamp G^1 incandescent, a proceed or clear traffic indication is given to a train moving from left to right in the direction of the arrow. Also, with the green lamp G^1 incandescent an indication current will flow due to the potential of the portion 109 of the transformer 106 applied between the plate and the filament of the lamp G^1 through the following circuit:—beginning at 15 the filament of the lamp G^1 , portion 109 of the secondary winding of the transformer 106, wires 110, 107, 111 and 112, front contact 113, of the track relay T^1 , wire 114, winding of the danger relay DR^1 , wires 115 and 116, from the plate to the filament of the lamp G^1 . The flow of this indication current which is uni-directional and pulsating in character, due to the rectifying effect of the lamp G^1 of the Fleming valve type, causes 20 the danger relay DR^1 to be energized, thereby preventing the danger lamp R^1 from being illuminated. If now, the filament of the green lamp G^1 should burn out or should the lamp be de-energized because one of the wires for 25 supplying energy thereto should become broken, indication current will no longer flow to the danger relay DR^1 , and this relay assumes its de-energized position, in which position current is applied to the primary winding of the transformer 120 through the 30 following circuit beginning at the secondary winding of the transformer 100, wires 101 and 121, back contact 122 of the danger relay DR^1 , wire 123 primary winding of the transformer 120, wires 124, 111 and 108 back to the 35 secondary winding of the transformer 100. The net result is, that the failure of the green clear lamp causes the red danger lamp to be energized, this to avoid the engineer passing 40 a dark signal which according to the rules governing train movements is to be taken as a danger signal. If now, the block in advance of the block J becomes occupied the line relay LR^1 assumes its de-energized position 45 whereas the track relay T^1 remains energized. Under this condition of the relays T^1 and LR^1 the caution lamp Y^1 is illuminated through the completion of the following circuit—beginning at the secondary winding of 50 the transformer 100, wire 101, front contact 102 of the track relay T^1 , wire 103, contact 104 of the line relay LR^1 in its de-energized position, wire 126, primary winding of the transformer 127, wires 128, 107, 111 and 108 55 back to the secondary winding of the transformer 100. With the caution lamp Y^1 illuminated a caution wayside signal indication is given and the indication current derived from this lamp Y^1 flows through a circuit including the danger relay DR^1 , which circuit

is substantially the same as the indication circuit for the lamp G^1 heretofore traced. That is, illumination of the caution lamp Y^1 prevents the danger lamp R^1 from being energized through the back contact 122 of the danger relay DR^1 and failure of the filament of the lamp Y causes energization of the lamp R .

Let us now assume that the block J is occupied, or the track relay T^1 is de-energized for some other reason, thus establishing danger traffic conditions.

Under this condition of the relays T^1 and LR^1 the danger relay DR^1 is de-energized for two reasons. In the first place, no indication current can flow from the indication circuits including the lamps Y^1 or G^1 because these lamps are de-energized; further, the contact 113 contained in this indication circuit is open, so that, the danger relay DR^1 is de-energized by reason of which the danger lamp S^1 will be illuminated because the energizing circuit for its transformer 120, heretofore traced, is completed. In other words, the three position light signal S^1 in Fig. 90 95 is one wherein the clear and caution lamps are controlled directly by relays governed in accordance with traffic conditions ahead and the danger lamp R^1 thereof is controlled by a relay which responds to indication current derived from one or the other of the proceed lamps, so that the danger lamp is not extinguished until a proceed lamp is illuminated, thereby affording a more adverse signal indication in case one 100 or the other of the proceed lamps Y and G is extinguished at a time when it should be illuminated.

In Fig. 4 has been illustrated another form of semi-automatic traffic controlling system, 105 which is in many respects the same as the semi-automatic systems illustrated in Figs. 1 and 2, but is somewhat more complete and provides additional cross-protection features. The additional cross-protection features include the provision of a cross-protection relay, which is connected in multiple with the main relay MR at all times except when the lever L is in the reverse position so that false energization of main relay MR causes 110 115 operation of the cross protection relay.

The track relays T and T^1 , the line relay LR , the main relay MR , the indication magnet IM , the lever L , the cross-protection relay CR , the danger relay DR and the signal lamps G , Y and R are substantially the same as those heretofore described, and the indication relays IR^1 and IR^2 are constructed and function the same as the indication relay IR heretofore described. The track relays T 120 and T^1 may be assumed to be connected in track circuits having the same relation to the signal S in Fig. 4 as do the track relays of Fig. 1 have to the signal S in such Fig. 1.

Under normal conditions when the lever L 130

is in its normal position the fact that the relays T and LR are energized does not result in the application of current to either the lamp G or the lamp Y, because the main relay MR is de-energized and with the main relay MR de-energized the transformers for feeding the lamps G and Y are disconnected from the source of energy and are also shunted; also with the danger relay DR de-energized by dropping of contact 228 of relay MR, the primary of transformer 200 is energized through the following circuit:—beginning at the terminal (B + or -) of a suitable transformer, wire 201, back contact 202 of the danger relay DR, wire 203, primary winding of the transformer 200, wires 204, 205, 206 and 207 to the common return wire C connected to the other side of said transformer. With the primary winding of the transformer 200 energized the filament of the danger signal lamp R is rendered incandescent thereby displaying a danger signal at the exit end of the block H (see Fig. 1). With the red lamp R illuminated the portion 209 of the secondary winding of the transformer 200 impresses a potential between the heated filament and plate of the lamp R thereby causing the flow of indication current through the following circuit:—beginning at the filament of the lamp R, portion 209 of the secondary winding of the transformer 200, wires 204, 205, 206, 207 and 212, contacts 36—37 of the cross-protection relay CR, wire 35 and winding of the cross-protection relay CR, wires 34 and 213, winding of the indication relay IR¹, contacts 214—215 controlled by the lever L, wires 216, 217, 226, 219 and 220 to the plate of the lamp R. With the filament of the lamp R incandescent, sufficient uni-directional current flows in the circuit just traced by reason of the rectifying valve action of the lamp R to cause the indication relay IR¹ to assume its normal left hand position and illuminate the indicating lamp r located in the tower adjacent the lever L. It is desired to point out that the relay MR is connected in multiple with the indication relay IR¹ when the lever L is in its normal position as is obvious from the circuit just traced, but by reason of the construction of this relay MR and the fact that the relay MR is one of the alternating current polyphase type, the application of this pulsating uni-directional current will not cause the main relay MR to assume its energized position.

It should be noted that if the lever L is moved to the half normal position no circuit changes take place except that the indication magnet IM is connected in multiple with the indication relay IR¹, and if the lever is moved from the reverse to the half-normal or indicating position, for the purpose of finally moving it to its normal position to unlock conflicting levers, that indication current will

flow from the lamp R through the circuit just traced, which current when the lever is in the half normal position causes the indication magnet IM in multiple with the indication relay IR¹ to be energized and the lever to be unlocked, thus permitting the operator to move the lever to the normal position, thereby unlocking the conflicting levers in a manner heretofore described. Let us assume, however, that when the lever is thus moved from the reverse to the half normal or indicating position, that the lamp R is not illuminated, possibly because its filament is burned out, or the like. If this is the case, no indication is received from lamp r or through IM and the operator is unable to complete the movement of his lever to the normal position, and therefore is unable to unlock the levers of conflicting traffic controlling devices.

Let us now assume, that the lever L assumes its normal position, and a false or unauthorized connection, due to a cross, or the like, is made with the wire 234 connected to the source B positioned at contact finger 40 of relay CR to the control and indication wire 226, and still the main relay MR will not assume the energized position because the presence of this unauthorized connection also causes alternating current to flow through the winding of the cross-protection relay CR the wire 212 and to the other terminal C of this source of energy. The flow of this alternating current through the cross-protection relay CR causes the cross-protection relay CR to open its contacts 40, 41 thereby disconnecting the common wire 239 leading from the "B" side of the alternating current source so that no further flow of alternating current is possible through the relay MR. It should be noted that the partial circuit just mentioned, through which current is permitted to temporarily flow when a false or unauthorized connection is made to the wire 226 leading to the main relay MR, is checked each time that an indication is received by the indication relay IR¹ in that the indication current must flow through it, so that, the integrity of this circuit is assured and the cross-protection relay CR is assured to be energized by alternating current resulting from such a cross, and thus cause the contacts 36—37 and contacts 40—41 to open. The opening of contacts 40—41 entirely cut off the source of alternating current used for feeding the proceed transformers 230 and 232 whereas the transformer 200 still has a source of alternating current available, as clearly shown.

Thus far, in connection with the description of Fig. 4 of the drawings, the lever L has been assumed to be in the normal danger position or in the half normal indication position.

Let us now assume that the operator moves the lever L to the reverse or proceed posi-

tion, and that the track relays T and T¹, and therefore the line relay LR are energized. Under this condition the main relay MR is energized through a circuit which may be traced as follows:—beginning at the terminal B, contacts 223—224 controlled by the lever L, wire 225 control and indication wire 226, winding of the main relay MR, wires 205, 206, 207 to common return wire C connected to the other side of said source of alternating current. With this circuit completed the main relay MR assumes its energized position and since traffic conditions are assumed to be favorable, current is applied to the primary winding of the transformer 230 through the following circuit:—beginning at the terminal B of said alternating current source contacts 40—41 of the cross-protection relay wire 229, front contact 231 of the track relay T, wire 232, front contact 233 of the line relay LR, wire 234, contacts 235—236 controlled by the lever L, wires 237 and 238, front contacts 239 of the main relay MR, wire 240, primary winding of the transformer 230, wires 241 and 242, front contact 243 of the main relay MR, wires 244, 245, 246, 206 and 207 to the common return wire C connected to the other terminal of said alternating current source. With this circuit completed the filament of the lamp G is rendered incandescent and its incandescence causes an indication current to flow through the indication relay IR² through the following circuit:—beginning at the filament of the lamp G, the portion 247 of the secondary winding of the transformer 230, which produces the necessary potential to cause this indicating current to flow, wires 241 and 242, front contact 243 of the main relay MR, wires 244, 245, 246, 206 and 248, winding of the indication relay IR², wires 249, 250 and 251 to the plate of the lamp G and through the ionized gap between the plate and the filament of this lamp. This uni-directional pulsating current flows in a direction in the circuit just traced so as to cause the indication relay IR² to assume the right hand dotted position, thereby energizing the proceed indication lamps g—y located in the tower adjacent the lever L. There is also another indication circuit through which current rectified by the lamp G flows which energizes the danger relay DR, which circuit is readily traced in the drawings, this relay DR being connected in multiple with the indication relay IR² through a partial circuit including front contact 228 of relay MR. With the danger relay DR energized current is cut off of the transformer 200 so that the danger lamp R is extinguished. It should, however, be noted that failure of the lamp G, possibly because its filament is burned out, causes the flow of indication current to cease and causes the relay DR to assume its de-energized position, thereby illuminating the danger lamp R. This illumination of the danger lamp R, how-

ever, does not cause the indication lamp r in the tower to be illuminated because the lever L is in the reverse position and the indication relay IR¹ is disconnected from the indication circuit, but de-energization of the indication relay IR² gives the necessary information to the operator.

If the lever L is in the reversed position, as has been assumed, and there is a train in the block containing the track relay T¹ the line relay LR assumes its de-energized position thereby causing the lamp Y instead of the lamp G to be energized for reasons obviously from the circuit arrangement, and therefore needs no detailed discussion. With the lamp Y energized the danger relay DR is energized by indication current derived from the lamp Y through a circuit similar to that traced in connection with the illumination of the lamp G above, so that, the failure of the filament of the lamp Y, or any essential circuit connection leading to this lamp, causes the danger relay DR to be de-energized and in turn causes the danger lamp R to be illuminated.

It should be noted, that the primary windings of the transformers 230 and 232 are short circuited by the contacts 239 and 253 when the relay MR is in its de-energized condition, and that the wires 237 and 254 are connected together and to the common return wire C by back contacts 255 and 256 through the following partial circuit:—beginning at the contacts 255 and 256 of the main relay MR, wires 257, 219, 226, 217 and 216, contacts 214—215, winding of the indication relay IR¹, wire 213, winding of the cross-protection relay CR, wire 35, contacts 36—37 of the cross-protection relay CR, wire 208 to common return wire C. The flow of current in the partial circuit just traced due to false or unauthorized connection to the wires 237 or 254 or any wires associated therewith when the lever is in the normal position causes the cross-protection relay CR to disconnect the main wire 239 from the terminal B; also, if the main relay MR should assume its de-energized position by reason of a break in its energizing circuit at a time when the lever is in its reverse position the application of current to the wires 237 or 254 through contacts 231 and 233 of the relays T and LR would cause the cross-protection relay CR to operate and disconnect the energy from the proceed portion of the system. Further, it should be noted that there is still another shunting circuit for the wires 237 and 254 which is closed under normal conditions, which includes the contacts 260—261 and 262—263 in multiple and from whence this shunting circuit comprising wires 264, 217, and 216, contacts 214—215, winding of the indication relay IR¹, wire 213, winding of the indication relay IR¹ wire 213, winding of the cross-protection relay CR, contact 36—37 of the cross-protection relay CR, wire 212 to the common return wire.

It is thus noted that in the arrangement shown in Fig. 4 practically every possible electro-responsive device which might cause a false indication if energized is shunted at a time when it should not be energized, that a cross-protection circuit including the cross-protection relay CR bridges the main relay MR under normal conditions, so that if current were applied to the main relay MR it would simultaneously be applied to the cross-protection relay CR which would cause this relay CR to disconnect the main connection leading to said source of alternating current, and that the partial cross-protection circuit just mentioned and including the control and indication wire 226 is checked each time an indication is received by the indication relay IR¹ or the indication magnet IM.

Having thus shown various traffic controlling systems which include various features embodying the present invention in various combinations, it is desired to be understood that the specific circuit arrangements illustrated have been chosen for the purpose of illustrating the invention rather than showing the specific manner in which the invention is preferably applied, and that various changes, modifications and additions may be made to adapt the invention to the particular problems and railway systems encountered in practice, without departing from the spirit or scope of the invention or the idea of means underlying the same.

What I claim is:—

- 35 1. In an interlocking system for railways employing light signals, the combination with a plurality of light signal units for each signal, a manually operable lever for controlling the illumination of said light signal units, automatic means for preventing said manually operable lever from effecting the display of a proceed indication when traffic conditions are dangerous, and automatic means for illuminating a danger lamp under favorable traffic conditions if the filament of a proceed lamp which should be lighted at the time is not incandescent.
- 45 2. In an interlocking system for railways employing light signals, the combination with a plurality of light signal units a manually operable lever for controlling the illumination of said light signal units, automatic means for preventing said manually operable lever from effecting the display of a proceed indication when traffic conditions are dangerous, and automatic means for indicating at the lever whether the filament of a proceed lamp or a danger lamp is incandescent.
- 55 3. In an interlocking system for railways employing light signals, the combination with a plurality of light signal units a manually operable lever for controlling the illumination of said light signal units, automatic means for preventing said manually oper-

able lever from effecting the display of a proceed indication when traffic conditions are dangerous, and automatic means for causing relay means to assume one position when a proceed lamp is illuminated and to assume a different position when a danger lamp is illuminated.

4. In a semi-automatic signal, the combination with a light signal having a plurality of light signal units, a lever having contacts for completing circuits for illuminating said signal units to give a proceed or a stop indication, automatic means for preventing a proceed indication from being given by movement of said lever when traffic conditions are adverse, and means for causing the flow of indication current of one characteristic if the filament of a light signal giving a favorable traffic indication is incandescent and for causing the flow of indication current of a different characteristic when a filament of a signal indicating adverse traffic conditions is incandescent.

5. In a semi-automatic signal, the combination with a light signal having a plurality of light signal units, a lever having contacts for completing circuits for illuminating said signal units to give a proceed or a stop indication, automatic means for preventing a proceed indication from being given by movement of said lever when traffic conditions are adverse, and means for causing a uni-directional current of one polarity to flow in an indication circuit when a favorable traffic indication is incandescent, and for causing a uni-directional current of opposite polarity to flow in an indication circuit when an adverse traffic indication is incandescent.

6. In a semi-automatic signal, the combination with a light signal having a plurality of light signal units each including an incandescent lamp having an anode therein, a lever having contacts for completing circuits for illuminating signal units to give a proceed or a stop indication, automatic means for preventing a proceed indication from being given by changing the position of said lever when traffic conditions are adverse, and means for giving distinctive indications at the lever in response to a wayside proceed or a stop indication respectively, said means including two circuits in each of which is included the ionized gap between the filament and the anode of one of the incandescent lamps of the signal, said gaps being so connected in the circuits that the relative disposition of the anodes and filaments is opposite.

7. In an interlocking system including a multiple aspect color light signal having a plurality of signal units the combination with an incandescent lamp for the unit of each signal, an anode in each lamp which in combination with the filament constitutes a Fleming valve, and indication circuits each including a source of alternating current, relay

means, and the gap between filament and anode of a lamp of the signal disposed in its indication circuit to cause said relay means to assume different energized positions respectively in response to valve action of said lamps.

8. In an interlocking system, the combination with a lever for controlling a multiple aspect color light signal, a lamp of the Fleming valve type for the stop signal unit of said light signal, a control relay which if energized extinguishes said stop signal unit a cross protection relay connected in multiple with said control relay when the lever is in the normal stop position so as to actuate said cross-protection relay if unauthorized current is accidentally applied to said control relay, said cross-protection relay if actuated cutting current off of the interlocking systems, whereby said control relay cannot be energized unless said cross protection relay is also energized, so long as said lever is in the normal stop position, and locking means for locking said lever against movement to the normal stop position effective unless the stop signal lamp is energized, said locking means being rendered ineffective by current derived by valve action from said Fleming valve type stop signal lamp.
- 30 9. In an interlocking system for railways employing light signals, the combination with a plurality of light signal units for each signal a manually operable lever for controlling the illumination of the light signal units, automatic means for preventing said manually operable lever from effecting the display of a proceed indication when traffic conditions are dangerous, automatic means for illuminating a danger lamp under favorable traffic conditions if the filament of a proceed lamp which should be lighted at the time is not incandescent, and automatic means for indicating at the lever whether the filament of a proceed lamp or a danger lamp is incandescent.

10. In an interlocking system, in combination, a lever for controlling a multiple aspect color light signal, a lamp of the Fleming valve type for the stop signal unit of said light signal, a control relay which is energized extinguishes said stop signal unit, a cross protection relay connected in multiple with said control relay when the lever is in the normal stop position so as to actuate said cross protection relay if unauthorized current is applied to said control relay, said cross protection relay if actuated cutting current off of the interlocking system whereby unauthorized current cannot operate such control relay so long as said lever is in the normal stop position, and indicating means rendered active if the gap of said Fleming valve is ionized.

11. In an interlocking system, in combination, a lever for controlling a multiple

aspect color light signal consisting of a plurality of light emitting units emitting light beams of different color of which only one is active at one time, a control relay which if energized extinguishes the stop light unit of said light signal, and a cross protection relay connected in multiple with said control relay when said lever is in the normal stop position so as to actuate said cross protection relay if unauthorized current is applied to said control relay, said cross protection relay if actuated cutting current off of the interlocking system, whereby unauthorized current cannot operate said control relay so long as said lever is in the normal stop position.

12. In an interlocking system, in combination, a lever for controlling a multiple aspect color light signal consisting of a plurality of light emitting units emitting light beams of different color of which only one is active at one time, a control relay which if energized extinguishes the stop light unit of said light signal, a cross protection relay connected in multiple with said control relay when said lever is in the normal stop position so as to actuate said cross protection relay if unauthorized current is applied to said control relay, said cross protection relay if actuated cutting current off of the interlocking system, whereby unauthorized current cannot operate said control relay so long as said lever is in the normal stop position.

In testimony whereof I affix my signature.

CHARLES W. PRESCOTT.
